WINDOW FRAME

Anton A. Guillaume, La Crosse, Wis., assignor to
Segelke & Kohlhaus Company, La Crosse, Wis.,
a corporation of Wisconsin

Application April 29, 1931. Serial No. 533,709

13 Claims. (Cl. 20—11)

This invention relates to window frames. It will be described as incorporated in a window frame constructed of wood or similar material and of the type extensively used in the construction of dwelling houses.

An object of this invention is the provision of a window frame which resists the leakage of air and moisture between the adjacent members of the frame.

Another object is the provision of such a frame which includes elements so formed and inter-fitted that the parts are readily retained in place while they are being secured together.

In the accompanying drawing, Fig. 1 is a perspective sectional view partly broken away and taken substantially on the vertical axis of a window frame incorporating my invention;

Fig. 2 is an enlarged fragmentary section of a portion of the head jamb and associated parts;

Fig. 3 is a vertical section through a window frame head section illustrating the prior construction as contrasted with my improved construction;

The frame shown in Fig. 1 comprises head and side jambs 5 and 6 respectively having grooves 7 and 8 therein in which are fitted window sash stops 9 and 11. Adjacent the outer edge of the jambs are provided semi-cylindrical grooves 12 and 13 in which are fitted the beads 14 and 15 on the blind stops 16 and 17 respectively. The blind stops 16 and 17 are of the same shape and as the stop 16 is shown in enlarged section in Fig. 2, it will be described more in detail.

The blind stop 16 includes a body portion 18 which is interposed between the outer edge 19 of the head jamb 5 and the inner side or face 21 of the head casing 22, which casing lies in a plane at right angles to the plane in which the head jamb 5 is positioned. The lower end 23 of the stop 16 extends a substantial distance below the lower edge 24 of the casing 22 so as to provide a means against which blinds, a screen or a storm sash may be positioned. The lower end 23 of the stop 16 extends inwardly a short distance under the lower face 25 of the jamb 5 and is adapted to have its inner face 26 engaged by a window sash or the like. As best shown in Fig. 2, it may be seen that the bead 14 is offset inwardly from the body portion 18 of the stop 16 a sufficient distance to make room for a substantially rigid bead or tongue 27 on the jamb 5 between the groove 12 and the outer edge 19.

When the parts 5 and 16 are snugly fitted together as shown in Fig. 2 they may be secured

together as by nails 28 without danger of relative slippage or movement between the jamb and the stop.

In order that the casing 22 may be accurately positioned and held in position while it is being nailed to the jamb 5 through the stop 16, I have provided a tongue or bead 29 which extends into a recess 31 in the face 21 of the casing 22. The groove 31 preferably has a beveled edge 33 engaging with a cooperating beveled edge 34 on the bead 29. By the use of such a beveled fitting, it is possible to make a substantially moisture proof joint, particularly so if white lead or the like is applied to the parts as they are being fitted together. A drip cap 36 is positioned on the upper edge of the head casing 22 and preferably secured thereto as by nails 37. The lower ends of the side casing 39 and the side jamb and side blind stop are positioned on and suitably secured to the window sill 41.

By a comparison of Fig. 2 with Fig. 3 it will be seen that my use of the specific stop construction having interlocking engagement with the jamb and the casing not only insures a more accurate assembly and permanent interlocking engagement of the parts when they are secured together as by nails 43, but no straight line joints such as illustrated at 45 and 46 in Fig. 3 are present in Fig. 2, the various engaging surfaces are irregular being broken by the grooves and tongues which form substantially air tight joints between the blind stop 16, the jamb 5 and the casing 22.

The advantage of having one side of the bead 29 flat—at right angles to the plane of the window—and the other side 34 beveled is this:

When the sides of a bead and groove are straight, the members can be pulled apart as far as the depth of the bead without opening up any air passage. If both sides of the bead and groove 95 are beveled, any pulling apart of the members opens up an air passage. On the other hand the advantage of having the sides beveled is that they center themselves and are more easily assembled and a tighter joint can initially be made 100 on account of the wedging action. By making one side straight and the other beveled, I retain the advantages of both types and also avoid the disadvantages of both.

Thus the beveled side 34 of the bead 29 makes 105 for an easy assembly and initially wedges the bead into a firm engagement with the groove especially on the opposite or straight side. If the casing should draw away from the stop, there would ordinarily be no tendency toward a 110

relative movement in a direction parallel to the window and if there were, it would be checked by nail 43. Thus the straight side of bead would continue to engage the straight side of the groove 5 with the result that no passage would be opened up. There would however be a slot opened up across the beveled side and across the bottom of the groove. I prefer to have the straight side come on the side nearest the weather, so that 10 there is less danger of water working into the slot which would thus be opened up, because the water would not be able to pass the engagement between the straight side of the bead and the straight side of the groove.

15 In those instances where the blind stop is rabbeted into the jamb but is not interposed between the jamb and the casing, whereby the inside face of the casing directly contacts the outer edge of the jamb, or frame member, the bead 29 20 would be formed on the edge of the jamb.

The nails 28 and 43 are not relied upon to hold the stop against the edge of the jamb, because that function is performed by the interlocking bead 14 and groove 12. The nails however do 25 serve the function of preventing relative movement of the stop and jamb in a direction parallel with the window. This is a shearing strain pull upon the nails rather than a pulling strain, and therefore the nails are much better able to continue successfully to perform this function.

30 Even apart from the foregoing function of the nails, the two beads 29 and 14 cooperate to maintain a tight seal of the blind stop against the jamb. The seal afforded by the groove 12 and the tongue 14 is one which resists relative movement of the parts transversely of the window but not in a direction parallel with the plane of the window. But movement of the blind stop away from the jamb in a direction parallel with the plane of the window is precluded by the tongue 29 which enters the groove 31 in the casing.

35 It will be understood by those skilled in the art that although I have shown a specific embodiment of my invention, it is susceptible of 40 various forms and modifications without departing from the principle thereof as more particularly set forth in the appended claims. In the absence of other recognized generic term, I have used the term "jamb" in the claims in the broader sense of including both the side jamb and the so-called head jamb.

I claim as my invention:

1. In a window frame in combination, a jamb 55 and a blind stop contiguous thereto, and interlocking tongue and groove members, one carried by the blind stop and the other carried by the jamb with the tongue member extending in a direction parallel with the plane of the window, for holding the blind stop and the jamb against relative movement in a direction transverse to the plane of the window.

60 2. In a window frame in combination, a casing having a groove in its inner side adjacent its inner edge, a jamb lying in a plane at right angles to the plane of said casing, said jamb having a groove in its inner side adjacent its outer edge, a blind stop interposed between said casing and said jamb and comprising beads projecting at right angles to each other, and extending 65 into said grooves to form interlocks between the blind stop and the adjacent members whereby relative slippage of the interlocking members is prevented.

70 3. In a window frame in combination, a casing 75 having a groove in its inner side adjacent its

inner edge, a jamb lying in a plane at right angles to the plane of said casing, said jamb having a groove in its inner side adjacent its outer edge, a blind stop including projecting portions fitting within the grooves in the casing and 80 in the jamb to effect interlocks and sealed joints therewith.

4. In a window frame in combination, a casing having a groove in its inner side adjacent its inner edge, a jamb lying in a plane at right 85 angles to the plane of said casing, said jamb having a groove in its inner side adjacent its outer edge, a blind stop interposed between said casing and said jamb and comprising portions interlocked to effect sealed joints therebetween.

5. A frame for a window, comprising a jamb, a 90 casing, a blind stop therebetween, an interlocking bead and groove engagement between the stop and casing with the bead projecting in a direction transverse to the plane of the window and 95 an interlocking bead and groove engagement between the stop and the jamb with the bead projecting in a direction parallel to the plane of the window.

6. A frame for a window, comprising a jamb, a 100 blind stop and an interlocking bead and groove engagement therebetween with the bead projecting in a direction parallel with the plane of the window.

7. A frame for a window, comprising a jamb, a 105 casing, a blind stop therebetween and means for holding the stop against the jamb comprising interlocking bead and groove members, one member carried by the jamb and the other by the stop, the bead projecting in a direction parallel with the window.

8. A frame for a window, comprising a jamb, a 110 casing, a blind stop therebetween and means for holding the stop against the jamb comprising interlocking bead and groove members, one member carried by the jamb and the other by the stop, the bead projecting in a direction parallel with the window, and a nail passing through the stop and into the jamb in a direction transverse to the window to hold the bead 115 and groove in interlocking engagement.

9. A frame for a window, comprising a jamb, a 120 casing, a blind stop therebetween and means for holding the stop against the jamb comprising interlocking bead and groove members, one member carried by the jamb and the other by the stop, the bead projecting in a direction parallel with the window, and an interlocking bead 125 and groove connection between the stop and the casing to hold the jamb against movement in a 130 direction parallel with the window.

10. A frame for a window, comprising a jamb, a 135 casing, a blind stop therebetween and means for holding the stop against the jamb comprising interlocking bead and groove members, one member carried by the jamb and the other by the stop, the bead projecting in a direction parallel with the window, a portion of the jamb overlying the inner face of the jamb at the region 140 of said bead and groove.

11. A frame for a window, comprising a frame member extending transversely of the window, a casing engaging the forward edge of the frame member, interengaging bead and groove portions, one portion carried on the rearward face 145 of the casing and the other on the forward edge of the frame member, the bead projecting in a direction transverse to the window, one side of the bead and the mating side of the groove being substantially at right angles to the inside face 150

of the casing and the other side being beveled for the purpose specified.

12. A frame for a window, comprising a frame member extending transversely of the window, 5 a casing engaging the forward edge of the frame member, interengaging bead and groove portions, one portion carried on the rearward face of the casing and the other on the forward edge of the frame member, the bead projecting in 10 a direction transverse to the window, one side of the bead and the mating side of the groove being substantially at right angles to the inside face of the casing and the other side being beveled for the purpose specified, the beveled side 15 being the side away from the window.

13. The combination with a window frame including a jamb of a blind stop contiguous to the

jamb, interlocking tongue and groove members, one carried by the blind stop and the other carried by the jamb with the tongue member extending in a direction parallel with the plane of the window, for holding the blind stop and the jamb against relative movement in a direction transverse to the plane of the window, and a second tongue and a second groove, one carried by the blind stop and the other carried by the frame with second tongue extending in a direction transverse to the plane of the window for holding the blind stop and the jamb against relative movement in a direction parallel with the plane of the window and which would tend to separate the first tongue and groove. 80 85 90

CERTIFICATE OF CORRECTION.

Patent No. 1,930,801.

October 17, 1933.

ANTON A. GUILLAUME.

It is hereby certified that error appears in the printed specification of the above numbered patent requiring correction as follows: Page 2, line 99, claim 4, after the syllable "locked" insert the words with the grooves thereof; and that the said Letters Patent should be read with this correction therein that the same may conform to the record of the case in the Patent Office.

Signed and sealed this 19th day of December, A. D. 1933.

Richard Spencer
